F. DIETERLE

ADJUSTABLE STRAP CONNECTION

Filed Jan. 21, 1928

By *Stan Middleton Donaldson & Hall*

By Spear Middleton Donaldson & Hall

Attorney

UNITED STATES PATENT OFFICE.

FRANK DIETERLE, OF PHILADELPHIA, PENNSYLVANIA, ASSIGNOR TO A. J. REACH COMPANY, OF PHILADELPHIA, PENNSYLVANIA.

ADJUSTABLE STRAP CONNECTION.

Application filed January 21, 1928. Serial No. 248,413.

My said invention relates more particularly to the means for adjustably connecting the edges of the front and back pads of foot ball harness under the arms of the wearer.

Such connections has heretofore been made by means of elastic straps and to make these adjustable resort has been had to metallic buckles or like devices, but exposed metal parts in foot harness has been found unsatisfactory.

The present invention aims to provide a form of connection which will be free from any exposed metal fastenings, which can be readily adjusted, and which after adjustment will afford an effective lock against further movement no matter how much strain the strap is subjected to.

In order that the invention may be more readily understood reference is made to the accompanying drawing in which—

Figure 1 is a perspective of such harness or pad structure.

Fig. 2 is a section on line 2—2 of Fig. 1.

Figs. 3 and 4 are sectional details along the same section line illustrating the action of the locking piece.

Fig. 5 is a section on line 5—5 of Fig. 2, and

Fig. 6 is a perspective view of the push piece.

In this drawing the numeral 1 designates the front or breast pad, 2 the back pad, connected at the top and provided with the usual shoulder pads, all of which may be of the ordinary or any desired construction not necessary to be specifically described beyond the statement that each of the pads 1 and 2 comprise a leather facing 1^a and 2^a provided with cushion padding 1^b and 2^b usually of felt stitched to the leather facing, 3 designates the connecting strap of elastic webbing having one end attached firmly to the edge of one of the sections (2 for example), as by placing it between the leather and lining and stitching it securely in place.

The other section 1 has two spaced apart parallel slits 2^a and 2^c, and the other end of the strap 3 is threaded first through the slit 2^a and then back through slit 2^c and after thus being threaded through the slits has its end connected to a slider encircling or embracing the intermediate portion of the strap, which slider may be in the form of a leather loop 4, and is designed to secure adjustment of

the strap by increasing or decreasing the length of the loop.

55

In order to lock the looped portions firmly in the slotted pad under conditions of use and at the same time enable ready adjustment thereof I provide a locking piece in the shape of a relatively thin plate 5 of rigid material, preferably of hard fibre, though metal or other material may be used therefor. This locking piece is wider than the slots and lies between the loop forming portions of the strap within the leather facing of the pad, 60 its rear end being cut or shaped to form a recess for securing the rear end of the loop and side lugs 5^a which prevent the rear end of the loop from slipping off the corresponding end of the slider or becoming unseated 70 from the recess. The front end of the locking piece is provided with push means projecting through the slot 2^c and lying between the layers of the strap loop, which push piece preferably takes the form of an integral tongue 75 5^b of less width than the locking piece.

With the construction above described when it is desired to adjust the strap it is only necessary to press in the locking plate by means of its push piece whereupon the strap 80 may be shortened or lengthened by pulling on the corresponding exposed portion of the loop. Upon release of the locking piece and pulling on the strap the loop will be drawn through the slots until the front shoulders 5^c 85 contact with the unslotted portions of the pad facing on each side of the slit 2^c at which time the strap will be securely locked against further movement, and additional tension on the strap will only result in increasing the locking effect.

While I have described my invention as embodied in foot ball harness it will be obvious that it may be applied to advantage in other situations.

95

Having thus described my invention what I claim is—

1. In combination a unitary member having a pair of parallel slits, a strap having a looped portion threaded through said slits, 100 and an independent locking plate lying between the plies of the loop and movable relative to the portion of the member lying between said slits.

2. The device according to claim 1 in which 105 the locking plate has a tongue of less width

than the plate projecting through one of the slits.

3. In combination a member of sheet form having a pair of parallel slits, a strap having a looped portion threaded through said slits, and a flat locking plate lying between the plies of the loop and of a length exceeding the distance between said slits.

4. In combination a member of sheet form having a pair of parallel slits, a strap having a looped portion threaded through said slits, and a flat locking plate lying between the plies of the loop and of a length exceeding the distance between said slits, said locking

plate having a tongue of less width than the 15 plate and lying in the plane of the plate and projecting through one of the slits.

5. In combination, a member of flexible sheet material having adjacent the edge thereof a pair of parallel slits, a backing sheet 20 secured thereto on opposite sides of the pair of slits and forming a pocket, a strap threaded through said slits and forming a flat loop 25 lying within the pocket, and a flat locking plate lying within said loop and having a push extension projecting through one of the slits.

In testimony whereof I affix my signature.
FRANK DIETERLE.
